UNITED STATES PATENT OFFICE.

SIDNEY T. MALTBY, OF WASHINGTON, DISTRICT OF COLUMBIA.

CONTAINER.

1,217,799.

Specification of Letters Patent. Patented Feb. 27, 1917.

Application filed April 8, 1916. Serial No. 89,750.

To all whom it may concern:

Be it known that I, SIDNEY T. MALTBY, a citizen of the United States, residing at Washington, in the District of Columbia, 5 have invented certain new and useful Improvements in Containers, of which the following is a specification.

My invention relates to an improvement in containers, the object being to provide a 10 closure for receiving, storing and dispensing merchandise, such for example as ice-cream. It is so constructed that it can be both filled and emptied without touching the contents, thus rendering the handling of the merchandise contained therein both cleanly and 15 sanitary. One of the features which distinguishes this invention from others is a means for severing the container or package from one end to the other without disturbing the contents, thereby entirely loosening and removing the wrapper or container, leaving the contents (if it be ice-cream) frozen in a solid mass in the form of the container, without undergoing the inconvenience and difficulty generally experienced 20 by either heating the container to loosen it, touching the contents with the fingers, or digging it out with a spoon.

All this is accomplished by the special 25 construction of the package or container, which comprises a body portion having heads at each end, one of which at least is held in place by frictional contact, and a means connected with the body portion for 30 severing it and removing it from the contents without in any wise disturbing its form.

In the accompanying drawings:

Figure 1 is a view in perspective showing 35 the top partly removed; and

Fig. 2 shows the final operation of opening the package or container and exposing the contents untouched upon a plate, which latter is indicated in dotted lines.

40 A, is the body of the container, which in the two views is illustrated in the form of a cylinder for convenience, although not necessarily so. This is preferably made of a sheet of moderately stiff paper, say from 45 ten to twenty point tag-board, although this,

of course, is left entirely with the discretion of the manufacturer.

Both ends are preferably open and adapted to be closed when the container is filled by heads 1 and 2. These are generally inserted and held in place frictionally, although the lower head or bottom 2 might be stitched permanently in place as indicated by the dotted lines at 3. The ends of the body are brought together and overlapped, 55 as shown in Fig. 1, and are stitched as at 4. The ends 5, 5, of the threads forming these stitches on the upper and lower sides are left sufficiently long to extend across the container, as shown in Fig. 1. They are 60 adapted to be stitched thereacross and placed beneath the head or cover 1 and left protruding beyond the edge thereof, where they can be grasped by the operator, as shown in Fig. 1, when it is desired to remove the head 70 or cover 1. This is done by taking hold of the ends and lifting them, which lifts the head or cover illustrated in Fig. 1.

Now to rip open the side or body and remove the contents, the container is inverted 75 and may be placed on a plate, as shown in dotted lines in Fig. 2, and indicated by the numeral 6, whereupon the operator presses with his finger on the head or bottom 2, as shown in Fig. 2, and gives a smart upward 80 pull to the ends 5, 5, of the threads (as illustrated in Fig. 2) thus ripping the stitched overlapping end 7, which severs the body portion throughout its length, which latter 85 expands by its own natural tendency to straighten out, thus exposing the entire molded cake of cream, whereupon the container with the head 2 is removed, and the cream is ready to be served.

I claim:

1. A package or container, the body of which is made of material fashioned into shape, and having its ends brought together and fastened with a continuous stitch, the ends of the material forming the stitch being 95 of sufficient length to extend across the package or container, and over which one end of the package is placed, whereby the pulling of the ends will remove one head of the package or container and rip open the 100

stitched end of the body portion of the package.

2. A package or container, the edges of the body portion of which are brought together and stitched as the sole means of holding the edges together and the sole means of ripping the side of the package open when the contents is to be removed, and a lid or cover

inserted in the end of the package over the ends of the threads which form the stitching 10 and the initial pull of which removes the lid or cover preliminary to ripping open the stitched edges of the side of the package.

In testimony whereof I affix my signature.

SIDNEY T. MALTBY.
